PNEUMATIC GRANULE SUPPLYING
APPARATUS

Orville V. McGrew, Chicago, Ill.

Application August 21, 1939, Serial No. 291,238

1 Claim. (Cl. 91—44)

This invention relates to a pneumatic granule supplying apparatus, and more particularly to an apparatus for embedding granules in plastic coating compositions.

In my Patent No. 2,145,027, issued September 8, 1938, is disclosed a composition of asphalt and cork and a method of applying it to surfaces in coatings of appreciable thickness. In my co-pending application Serial No. 281,266, filed June 26, 1939, is disclosed a drying oil composition which may be applied in a similar manner.

In the case of either such compositions, or in other plastic coating compositions, it is frequently desirable to apply a coating of roofing type granules to the plastic material while it is still in a plastic state. The present invention relates to an apparatus adapted to embed such granules in the plastic coating a suitable distance.

The invention is illustrated in the drawings in which Figure 1 is a side elevation, partly broken away, of the apparatus; Figure 2 is an end elevation of the lower portion of the hopper and appurtenances; Figure 3 is a sectional elevation, partly in section, taken along the line 3 in Figure 2; Figure 4 is a sectional elevation, partly in section, taken along the line 4 in Figure 2; Figure 5 is a view, partly in cross-section, of the ejector nozzle; and Figure 6 is a cross-section, taken on the line 6 in Figure 5.

The device consists of a hopper 10 having sloping walls 11 at the bottom converging to an orifice 12. A nozzle 13 is positioned within a larger pipe 14 just below the orifice 12. The nozzle comprises a tubular portion 15 which is threaded at each end. The base of the tubular portion is screwed into a bushing 16 set in an end wall 17 of the pipe. A coupling 18, adapted to be connected to an air hose, is secured to the bushing outside of the pipe. A collar 19 is secured over the front end of the tubular portion 15 leaving a small space 20. The collar 19 is likewise provided with an orifice 21 of slightly smaller diameter than the orifice 22 in the tube 15. The pipe 15 shown is $\frac{1}{8}$ inch standard pipe and the opening 21 is suitably $\frac{5}{32}$ inch in diameter, or larger, up to the diameter of the pipe. The positioning of the opening 21 with respect to the mouth 12 of the hopper is quite critical. If it is set too far back, or if the opening 21 is improperly adjusted, the granules will not feed properly from the hopper 10, either not being drawn along by the air or else permitting the air to by-pass through the hopper. The respective positions shown in Figure 4 are ideal for granules of the

ordinary roofing size (10 to 20 mesh) and for the 2-inch standard pipe 14 and the $1\frac{1}{2}$ inch standard pipe 12.

Pipe 14 is connected to the line 25 leading to the cyclone 26. The cyclone is provided with an opening 27 at the top and a smaller opening 28 at the bottom, the latter being connected to the body of the cyclone, as shown in Figure 5, by the orifice 29. The opening 28, which forms the nozzle, in addition is provided with a further opening 30 within which is seated an elbow 31 connected to an independent air line 32. The elbow is tapped on the inside for a $\frac{1}{8}$ inch pipe 33.

As shown in Figure 6, the $\frac{1}{8}$ inch pipe is $1\frac{5}{8}$ inches long. One end of it is brazed closed and drilled with a $5\frac{1}{8}$ inch hole 34. The end of the pipe 33 is $\frac{1}{8}$ inch from the opening 28 which itself is tapped for a $\frac{3}{4}$ inch pipe. The opening 29 is tapped for a 1-inch pipe.

The passage of air to the nozzle 28 and through the granule line 25 is controlled by the diaphragm valve 50, shown in Figure 3. This comprises a flexible diaphragm 51, held in a chamber 52 with a spring 53 in engagement with the diaphragm, which ordinarily holds the plunger valve 54 in engagement with the valve seat 55, thereby shutting off the air from the line 25. A plunger 56 adjacent to the nozzle (Figure 1) controls the air in the auxiliary line 32, and, when this plunger is pressed, air passes through the line 32 from the air inlet 40. As soon as the air passes through line 32 the pressure in chamber 52 is reduced, thereby opening the valve 54. In securing this effect the opening of valve 41 is suitably adjusted to control the speed with which the diaphragm valve acts. The openings 57 assist in making this control more sensitive and also decreases the sensitivity of the diaphragm valve to variations in the line pressure from the compressor. As soon as the valve 56 is released, however, the pressure in chambers 51 and 52 equalizes and the spring 53 closes valve 54.

In operation of the device the hopper 10 is filled with granules of the proper size, the necessary air connection is made, and the plunger 56 is pressed. This produces a blast of air at 28 and shortly thereafter, the time being regulated by adjustment of the valves 41, 42 and 43, associated with lines 32 and 25, air is admitted through line 25 and commences to carry granules with it. The granules pass into the upper part of the cyclone 26 and are drawn downwardly and ejected from the nozzle 28, the dust in the meanwhile separating therefrom and passing out of

the opening 27. Granules are ejected with considerable force and embed themselves sufficiently to produce a very satisfactory binding action in the plastic material to which they are applied.

The amount of air pressure employed on the line 40 may vary considerably depending upon the type of granules, the type of plastic, and the length and size of hose line 25. Under most circumstances a pressure of 40 lbs. per square inch is most satisfactory. If the hose is too long, it may be necessary to throttle the pressure upon the line 32 because of the excessive pressure drop throughout the line 25.

I claim:

A granule applying apparatus comprising a hopper, a flexible hose connecting the hopper and a centrifugal cyclone device, a nozzle, pneumatic means for forcing granules from the hopper into the hose, and independent pneumatic means supplying air to the nozzle, said cyclone device comprising a chamber having a large opening at one end and a relatively small opening communicating with the nozzle at the other end and shaped to produce rapid centrifugal motion of the pneumatic stream carrying the granules therein.

ORVILLE V. McGREW.
